UNITED STATES PATENT OFFICE.

NADEAU L. BOURGEAULT, OF SAN FRANCISCO, CALIFORNIA, ASSIGNOR TO ROOS BROS., OF SAN FRANCISCO, CALIFORNIA, A CORPORATION OF CALIFORNIA.

DESIGN FOR AN EMBLEMATIC PIN.

Application filed June 22, 1925. Serial No. 13,860. Term of patent 3½ years.

To all whom it may concern:

Be it known that I, NADEAU L. BOURGEAULT, a citizen of the United States, residing at San Francisco, in the county of San Francisco and State of California, have invented a new, original, and ornamental Design for Emblematic Pin, of which the following is a specification, reference being had to the accompanying drawing, forming part thereof.

I claim:

The ornamental design for an emblematic pin, as shown.

NADEAU L. BOURGEAULT.
